UNITED STATES PATENT OFFICE.

LAWRENCE BRADFIELD, OF DELAWARE, OHIO.

BROODER.

Application filed June 29, 1921. Serial No. 478,866.

To all whom it may concern:

Be it known that I, LAWRENCE BRADFIELD, a citizen of the United States, residing at Delaware, in the county of Delaware and State of Ohio, have invented a certain new and useful Improvement in Brooders, of which the following is a specification.

Young chicks are subject to coldness of the feet hence it is important for their health and proper development that these members be kept warm, especially in the brooder. Moreover when their feet are cold the chicks tend to crowd together for mutual warmth and in doing so many are crushed and bruised or otherwise injured.

The principal object of the invention is to provide improved means whereby the entire floor of a brooder may be uniformly heated or without overheating it in a particular spot thus avoiding injury by crowding and crushing and individual injury by the burning of the feet.

My invention is embodied in the example herein shown and described, the features of novelty being finally claimed.

In the accompanying drawing forming part hereof—

Figure 1 is a vertical central longitudinal section on the line I—I Fig. 2.

Fig. 2 is a plan view with portions broken out and omitted.

In the views 5 designates the floor of the brooder, said floor being of sheet metal of oblong form and hollow throughout. The floor is supported upon sill 6, and further is surrounded by a closed rail or wall 7 as shown to confine the chicks to the floor.

At one end or side of the floor is a water heating chamber 8 surrounded by a jacket 8^a spaced from the water chamber to confine the heat. At its lower end the water heating chamber 8 communicates by means of a small pipe with the hollow floor while the upper end of the chamber is connected with the opposite side or end of the floor by means of a pipe 9 that is slightly inclined upward to a point where it dips for connection with the floor. The water chamber is heated by means of a lamp 10 or a suitable gas burner.

Supported above the rail and spaced from the upper edge thereof is a roof 11 from which the usual hover strips 12 are hung. It is obvious that because the roof is spaced from the upper edge of the rail fresh ventilating air is admitted from all sides to below the roof while the chicks are protected from drafts of chilling wind by the closed rail.

Water can be supplied to the floor, the inclined pipe and the water heater through an opening near the top of the latter provided with a cover 13.

When water is heated by the burner under the heater it circulates from the heater up the inclined or advance pipe through the floor and back to the heater, the arrows indicating generally the course of its travel.

In order to prevent the floor from burning the feet of the chicks, should the water become overheated, the floor should be covered with a layer 14 of paper or other slow conductor of heat. However, the large area of the exposed floor, as compared with the size of the inclined or advanced pipe 9, makes it practically impossible to overheat the water or burn or injure the chicks, and promotes an equable heat in the brooder.

The forms of the parts can be changed without departing from the gist of the invention as claimed.

What I claim is:

A brooder including, in combination, a fixed surrounding rail and a roof above and spaced from the upper edge of the rail in fixed and permanent relation to the rail, a floor consisting of a flat hollow water receiving structure extending horizontally in all directions under the roof and to the surrounding rail, a water heating chamber communicating with said hollow floor at one side thereof, and a pipe of relatively small capacity as compared with the capacity of the floor connecting said heater with the other side of the floor, said pipe extending above the floor and under the roof.

LAWRENCE BRADFIELD.
